LABEL CUTTING AND FOLDING MACHINE.
APPLICATION FILED MAR. 11, 1912.

Patented July 21, 1914.

4 SHEETS—SHEET 4.

UNITED STATES PATENT OFFICE.

ARTHUR ROSENTHAL, OF GRAND RAPIDS, MICHIGAN, ASSIGNOR TO ROSE LABEL
MACHINE COMPANY, OF GRAND RAPIDS, MICHIGAN.

LABEL CUTTING AND FOLDING MACHINE.

1,104,316.

Specification of Letters Patent. Patented July 21, 1914.

Application filed March 11, 1912. Serial No. 683,666.

To all whom it may concern:

Be it known that I, ARTHUR ROSENTHAL, a citizen of the United States, residing at Grand Rapids, county of Kent, State of Michigan, have invented certain new and useful Improvements in Label Cutting and Folding Machines, of which the following is a specification.

This invention relates to label cutting and 10 folding machines.

Labels for apparel and various fabrics and articles are frequently stamped on or woven into a tape, which is cut off in lengths and stitched to the thing to be marked or 15 labeled after a seam has been folded thereon. So far as applicant can find out up to the present time, this cutting and folding operation has only been successfully done by hand and is a very tedious process and aside from 20 that, when completed, is not in the best form, being more or less defective.

This invention has to do with providing a machine with a cutting means for cutting off the tape and a folding means for folding 25 seams upon the ends of the tape immediately the same is cut off, and to improved feed devices which grasp the label, feed it to the cut-off device and pass it on through a folding device, and effectively creasing the seam 30 part and passing the same onward and depositing it in a suitable receptacle.

From this statement, the general objects of the invention will appear, and further objects relating to details and economies of 35 construction and operation will definitely appear from the detailed description to follow.

I accomplish the objects of my invention by the mechanism described in the following 40 specification. The invention is clearly defined and pointed out in the claims.

A machine which constitutes a preferred embodiment of my invention is fully illustrated in the accompanying drawing, forming 45 a part of this specification, in which:

Figure I is a perspective view of a machine embodying the features of my invention, a portion of the label reel being broken away to show details. Fig. II is a vertical 50 longitudinal sectional elevation view taken on a line corresponding to line 2—2 of Fig. III, showing the details and arrangement of the various parts. Fig. III is an inverted plan view of the machine with the main 55 frame detached from its base. Fig. IV is an

enlarged detail plan view of the central plate 18 and the parts supported by and coöperating therewith, somewhat enlarged, the guide for the vertical presser bar 23 being omitted. Fig. V is an enlarged detail sectional view on a line corresponding to line 5—5 of Figs. II, III and IV. Fig. VI is an enlarged detail sectional view on a line corresponding to the broken line 6—6 of Figs. II and III, the label receiver at the back being detailed, and parts thereof and of the frame and base being broken away. Fig. VII is an enlarged detail horizontal sectional view on line 7—7 of Fig. VI, showing the stationary cutting blade of the shears 70 and the means for adjusting the same. Fig. VIII is an enlarged detail transverse sectional view on line 8—8 of Fig. V, showing the method of adjustment of the feed member. Fig. IX is an enlarged detail sectional 75 view on line 9—9 of Fig. V, showing the method of taking up the slack in the eccentric loop or bearing, and the means for insuring proper adjustment of the same. Fig. X is an enlarged detail sectional view on 80 line 10—10 of Figs. II and III showing details of the ratchet actuating means for driving the creasing rollers step by step as the folded label is advanced to them by the feeding means. Fig. XI is an enlarged detail 85 transverse sectional view on a line corresponding to line 11—11 of Figs. IV, V and VI, showing details of the center plates and the feeding and folding devices. Fig. XII is an enlarged detail sectional view on a line 90 corresponding to line 12—12 of Figs. II and IV, showing the means for exerting pressure upon the creaser rolls 35, 36. Fig. XIII is a detail sectional view on line 13—13 of Fig. III showing the means for adjusting the 95 guide block for the reciprocating blade of the cut-off shears to bring the same into proper relation with the stationary blade, and to cut the label off at any length within the capacity of the machine. Fig. XIV is 100 a longitudinal sectional view through the label reel and its supporting means taken on a line corresponding to line 14—14 of Fig. I. Fig. XV is a detail perspective view somewhat enlarged of the label after it has 105 been cut from the strip and folded, forming the seam. Fig. XVI is a detail sectional view taken on line 16—16 of Fig. VI, showing details of the clamp means for the knife 56.

In the drawing, the sectional views are taken looking in the direction of the little arrows at the ends of the section lines, and similar numerals of reference refer to similar parts throughout the several views.

Considering the numbered parts of the drawing, the main frame 1 of the machine is removably supported in the base 2 by means of the adjustable attaching bolts 4, on which 10 are disposed the knurled thumb nuts 3 suitably shouldered at 5 to fit into corresponding slots 6 in an upwardly-projecting rim on the said base 2.

The machine is driven by a pulley 7 which 15 is carried on a shaft 8 supported in a suitable journal bearing in the said frame or case 1. The shaft is retained in definite position by suitable collars or otherwise. The feed member 10 embraces an eccentric 20 11 which is secured to the said shaft 8. The feed member 10 is supported on the shaft 12 and is suitably slotted at 13 so that it plays and oscillates freely back and forth thereon as it is actuated by the eccentric 11, thus insuring 25 the intermittent feed action of a four motion sewing machine feed. The serrated feed plate 9 is carried by the feed member 10 and is adjustably secured in position by clamp screws 14-14, the angle of the same 30 and its proper leveling and adjustment being maintained by the set screws 15-15. (See particularly Figs. IV and VIII.)

The tooth plate 9 is formed of longitudinal parallel serrated sections 16-16 which 35 reciprocate between bars 17, which are formed integral with the center or work plate 18, which serve as a guiding means for said feed. The bars 17 of the work plate support the label as it is being advanced. 40 This work plate is detachably secured in place by screws 19, as clearly appears from Figs. I, III and IV.

The feed member 10 is slotted at 10' to the eccentric and forms an adjustable eccentric ring which is adjusted to properly fit the eccentric 11 by the set screws 20, 21, the set screw 20 adjusting the width of the opening and the set screw 21 clamping the parts securely and rigidly together. See Fig. IX.

50 An upper bent arm 22, somewhat like the arm of a sewing machine, is secured to the top plate of the frame by a set screw 22'. In the front end of this arm is a vertically reciprocating presser bar 23 supported in suitable guides therein retained by guide plate 24 which guide plate is secured to the arm by a set screw 25.

To the lower end of the presser bar 23, 60 presser foot 26 is secured and coacts with the feed member 10. It acts very like the presser foot of a sewing machine. This presser foot is pivoted by the transverse screw pivot 27 through a suitable bracket 26' thereon. This presser foot contacts with the 65 upper side of the bars 17, is smooth on its

under surface and coacts with the serrated bars of the feed plate 9. The upright presser bar 23 is urged downwardly by means of the blade spring 28 which is secured by screw 29 to the upper side of the 70 arm 22, tension being adjusted by the set screw 30. (See particularly Figs. I and II).

Folder guide plates 31-31, having upwardly and inwardly curved portions 32, are secured to the upper side of the plate 18 by 75 screws 33, and are disposed at each side of the pressure plates 26 and are in proximity to the said plate at each side and coact therewith. When a label is advanced under the pressure foot by the feed member, the edges 80 of the label are folded upwardly and then as the same is advanced, inwardly by curved portions 32-32. The front part of the plates 31 are merely folded vertically and not inward.

On a suitable shaft 34 are disposed a pair of creaser rolls 35-36 which receive the label from the feed and crease the folded labels. A forwardly-extending guard spring 42 which is secured by a screw 43 to the 90 bracket 26' on the upper side of the plate is provided to insure the delivery of the labels beyond the rolls. The creaser rolls 35, 36 are urged into yielding contact with the top of the work plate 18 by yielding journal 95 bearings for the ends of the said shaft 34, the tension of which is adjustable, as will be seen from an examination of Figs II, IV, V and XIII. A yielding journal bearing 38 is properly retained and guided in position 100 by the housing 39, the upper portion of which constitutes a socket 37, into which is inserted a pressure spring 40, the tension of which is adjustable by means of the screw 41.

The shaft 34 which carries the creaser 105 rolls is rotated step by step by means of the ratchet wheel 44 which is acted upon by the pawl tooth 45 carried by the pawl 46, which is supported on an eccentric 47 on the shaft 8. The pawl is held in yielding contact by the spiral spring 48 which connects from the same to the top plate of the case, all of which parts clearly appear in detail in Fig. X, and in position in Figs. II and III from 110 which the said view is taken.

115 A stationary cutter blade 49 constituting a member of the cut-off shears, is carried by the adjustable block 50, a clip 51 securing the same in position by means of the set screw 52. This block 50 is provided with a suitable lateral extension, which fits into a suitable transverse seat 55 on the under side of the top plate, and is retained adjustably by set screws 53 which fit through slots 54 therein, as clearly appears in Figs. III 120 and VI.

The reciprocating blade 56 of the shears is notched at 56', see Figs. I and VI, and is reciprocated in proximity to the stationary blade 49. The two constitute a pair of 125 130

shears. The reciprocating blade is carried by the reciprocating member 57, which is pivoted on the shaft 12 and is actuated by the eccentric 58 which rotates in the slot 58' in the said reciprocating member. The dimension of the slot 58' to secure close fit to the eccentric 58 is insured by a pair of set screws 59, 60, which are comparable with the set screws 20 and 21, as illustrated in Fig. 10 IX. The eccentric 58 being adjustable on the shaft 8 is, of course, actuated whenever that shaft is actuated and can be turned to snip off the tape or label strip as the same is fed up step by step, as will be clearly seen by an inspection of Figs. I and VI.

The reciprocating member 57 is guided by the guide block 61, which is adjustable in suitable ways on the under side of the case top, see Figs. III and XIII, being secured effectively in place by the set screw 62 in the slot 63 therein. The adjustment is very effectively secured by the adjusting set screw 64, which is locked in place by the lock nut 65 whenever the correct adjustment is secured.

An arm 66 secured by screws 67 is provided for carrying the ribbon or label spool, a spindle 69 having a head 70 being secured to this arm by a set screw 71. The spool is made up of a body or barrel 72 with cheek pieces 73—73', a spring washer 73' putting tension upon the same to insure proper feeding of the ribbon. The tape or strip of labels 74 is wound thereon, as clearly appears in Figs. I and XIV, or the spools of tape can be inserted by removing the spindle. The roll of labels is placed upon this spindle and they are then fed one at a time to the machine. As these are grasped by the feeding device, they are advanced step by step forward and the strip, as it is advanced, is cut off little by little by the cut-off shears. As the label thus cut off is advanced, the edges of the same are turned upwardly by the upwardly-projecting portions of the guide plates 31—31, and as the same are advanced to the inturned portions 32—32, when the inner ends are folded over the edges of the pressure foot 26 and pass on under the spring 50 pressed creaser rolls 35—36, which compresses the same very closely, creasing the seam so that the same remains in a compactly folded position, as clearly illustrated in Fig. XV. The labels can then be very quickly and readily sewed in place. A box 76 held by hooks 77 (see Fig. VI), is provided to receive the folded labels.

I have thus described my improved label cutting and folding machine very minutely. I desire to state that the same can be greatly varied in details without departing from my invention. I know from experience that the same can be successfully operated without the creaser rolls 35—36, but the creaser rolls 65 are of very great advantage in securing the

effective creasing of the seams. The cut-off shears can, of course, be very effectively used without the remaining features for cutting off the labels at exactly the right length and doing the same effectively. The folding and creasing device could be used independent of the cutting off device, but all the devices coöperate very effectively together and are so associated that each coöperates with the other, constituting a complete unitary structure.

Having thus described my invention, what I claim as new and desire to secure by Letters Patent is:

1. In a label cutting and folding machine, the combination of a suitable frame; a shaft with suitable driving means; an oscillating feed member; an actuating eccentric on said shaft for actuating the same to secure a step-by-step four-motion feed movement; a feed plate of parallel serrated bars adjustably supported on said feed member; a work plate with suitable central guide bars intermeshing with the toothed bars of said feed plate; a vertical pressure bar; a spring for urging the same downwardly; a pressure shoe pivoted to said pressure bar coöperating with the said feed member; a pair of spring pressed creaser rolls disposed at the end of said pressure plates for creasing said labels; means for actuating said creaser rolls; guards extending from said pressure shoe to said creaser rolls; a cut-off shear consisting of stationary blade and a reciprocating blade coöperating therewith; suitable means coöperating with said feed for actuating said shears; and folder plates at each side of the pressure shoe to receive and fold the labels that are cut off and advanced by the said feed device onward to the creaser rolls for creasing the same, coacting for the purpose specified.

2. In a label cutting and folding machine, the combination of a suitable frame; a shaft with suitable driving means; an oscillating feed member; an actuating eccentric on said shaft for actuating the same to secure step-by-step four-motion feed movement; a feed plate of parallel serrated bars adjustably supported on said feed member; a work plate with suitable central guide bars intermeshing with the toothed bars of said feed plate; a vertical pressure bar; a spring for urging the same downwardly; a pressure shoe pivoted to said pressure bar coöperating with the said feed member; a pair of spring pressed creaser rolls disposed at the end of said pressure plates for creasing said labels; means for actuating said creaser rolls; a cut-off shear consisting of stationary blade and a reciprocating blade coöperating therewith; suitable means coöperating with said feed for actuating said shears; and folder plates at each side of the pressure shoe to receive and fold the labels that are cut off and ad-

vanced by the said feed device onward to the creaser rolls for creasing the same, coacting for the purpose specified.

3. In a label cutting and folding machine, 5 the combination of a suitable frame; a shaft with suitable driving means; an oscillating feed member; an actuating eccentric on said shaft for actuating the same to secure step-by-step four-motion feed movement; a work 10 plate with suitable central guide bars intermeshing with the toothed bars of said feed plate; a vertical pressure bar; an adjustable spring for urging the same downwardly; a pressure shoe pivoted to said pressure bar 15 coöperating with the said feed member; a pair of spring pressed creaser rolls disposed at the end of said pressure plates for creasing said labels; means for actuating said creaser rolls; a cut-off shear consisting 20 of stationary blade and a reciprocating blade coöperating therewith; suitable means co-operating with said feed for actuating said shears; and folder plates at each side of the pressure shoe to receive and fold the labels 25 that are cut off and advanced by the said feed device onward to the creaser rolls for creasing the same, coacting for the purpose specified.

4. In a label cutting and folding machine, 30 the combination of a suitable frame; a shaft with suitable driving means; an oscillating feed member; an actuating eccentric on said shaft for actuating the same to secure step-by-step four-motion feed movement; a feed 35 plate of parallel serrated bars adjustably supported on said feed member; a work plate with suitable central guide bars intermeshing with the toothed bars of said feed plate; a vertical pressure bar; a spring for 40 urging the same downwardly; a pressure shoe pivoted to said pressure bar coöperating with the said feed member; a pair of spring pressed creaser rolls disposed at the end of said pressure plates for creasing said 45 labels; a ratchet wheel for advancing said feed rolls; a ratchet pawl for acting on said ratchet wheel; an eccentric on said shaft for actuating said pawl; a cut-off shear consisting 50 of stationary blade and a reciprocating blade coöperating therewith; suitable means coöperating with said feed for actuating said shears; and folder plates at each side of the pressure shoe to receive and fold the labels 55 that are cut off and advanced by the said feed device onward to the creaser rolls for creasing the same, coacting for the purpose specified.

5. In a label cutting and folding machine, 60 the combination of a suitable frame; a shaft with suitable driving means; an oscillating feed member; an actuating eccentric on said shaft for actuating the same to secure step-by-step four-motion feed movement; a feed 65 plate of parallel serrated bars adjustably supported on said feed member; a work

plate with suitable central guide bars intermeshing with the toothed bars of said feed plate; a vertical pressure bar; a spring for urging the same downwardly; a pressure shoe pivoted to said pressure bar coöperating 70 with the said feed member; a pair of spring pressed creaser rolls disposed at the end of said pressure plates for creasing said labels; means for actuating said creaser rolls; a cut-off shear consisting of stationary blade and 75 a reciprocating blade coöperating therewith; a suitable oscillating member for carrying said reciprocating blade; an eccentric on said shaft for actuating the said reciprocating blade; and folder plates at each side of 80 the pressure shoe to receive and fold the labels that are cut off and advanced by the said feed device onward to the creaser rolls for creasing the same, coacting for the purpose specified.

6. In a label cutting and folding machine, 85 the combination of a suitable frame; a shaft with suitable driving means; an oscillating feed member; an actuating eccentric on said shaft for actuating the same to secure step-by-step four-motion feed movement; a feed 90 plate of parallel serrated bars adjustably supported on said feed member; a work plate with suitable central guide bars intermeshing with the toothed bars of said feed plate; a pressure shoe coöperating with the said feed member; a pair of spring presser 95 creaser rolls disposed at the end of said pressure plates for creasing said labels; means for actuating said creaser rolls; a cut-off shear consisting of stationary blade and a reciprocating blade coöperating therewith; suitable means coöperating with said feed for actuating said shears; and folder plates at each side of the pressure shoe to receive 100 and fold the labels that are cut off and advanced by the said feed device onward to the creaser rolls for creasing the same, coacting for the purpose specified.

7. In a label cutting and folding machine, 110 the combination of a suitable frame; a shaft with suitable driving means; an oscillating feed member; an actuating eccentric on said shaft for actuating the same to secure step-by-step four-motion feed movement; a feed 115 plate of parallel serrated bars adjustably supported on said feed member; a work plate with suitable central guide bars intermeshing with the toothed bars of said feed plate; a pressure shoe coöperating with the said feed member; a cut-off shear consisting of stationary blade and a reciprocating blade coöperating therewith; suitable means coöperating with said feed for actuating said shears; and folder plates at each side of the 120 pressure shoe to receive and fold the labels that are cut off, coacting for the purpose specified.

8. In a label cutting and folding machine, 125 the combination of a suitable frame; a shaft 130

- with suitable driving means; an oscillating feed member; an actuating eccentric on said shaft for actuating the same to secure step-by-step four-motion feed movement; a feed plate of parallel serrated bars adjustably supported on said feed member; a work plate with suitable central guide bars intermeshing with the serrated bars of said feed plate; a pressure shoe coöperating with the 5 said feed member; a cut-off shear coöperating with said feed; and folder plates at each side of the pressure shoe to receive and fold the labels that are cut off, coacting for the purpose specified.
- 10 15. 9. In a label cutting and folding machine, the combination of a suitable frame or casing; a feeding device with an oscillating member; a pressure plate or shoe coöperating therewith; creaser rolls; means for 20 actuating said creaser rolls; a cut-off means; and folder plates at each side of the pressure plate or shoe to receive the labels that are cut off and advanced by the said feed device 25 onward to the creaser rolls for creasing the seams therein, coacting for the purpose specified.
10. In a label cutting and folding machine, the combination of a suitable frame or casing; a cut-off means; a feeding device with 30 an oscillating member to advance the label laterally after it has been cut off; a pressure plate or shoe coöperating with said feeding device; folder means at each side of the pressure plate or shoe and feeding devices to receive and fold the cut off edges of the labels 35 that are cut off and advanced by the said feed device, and creaser rolls coacting for the purpose specified.
11. In a label cutting and folding machine, 40 the combination of a suitable frame or casing; a feeding device with an oscillating member; a pressure plate or shoe coöperating therewith; creaser rolls; means for actuating said creaser rolls comprising a ratchet 45 wheel for advancing said creaser rolls; a ratchet pawl for acting on said ratchet wheel; an eccentric on said shaft for actuating said pawl; a cut-off means; and folder plates at
- each side of the pressure plate or shoe to receive the labels that are cut off and advanced by the said feed device onward to the creaser 50 rolls for creasing the seams therein, coacting for the purpose specified.
12. In a label cutting and folding machine, the combination of a suitable frame or casing; a reciprocating feed device; a pressure plate or shoe coöperating therewith; creaser 55 rolls; a cut-off device consisting of a pair of shears comprising a stationary blade suitably adjustable and a reciprocating blade co-operating with said stationary blade; a suitable oscillating member for carrying said reciprocating blade; an eccentric on said shaft for actuating the said reciprocating blade; and folder plates at each side of the pressure 60 plate or shoe to receive the labels that are cut off and advanced by the said feed device, coacting for the purpose specified.
13. In a label cutting and folding machine, the combination of a suitable frame or casing; a cut-off means; reciprocating feed devices disposed for advancing the cut off label laterally; folder devices coöperating with the said feed devices to fold the cut off 65 edges and creaser rolls for receiving and creasing a label, as specified.
14. In a label cutting and folding machine, the combination of a suitable frame or casing; a cut-off means; reciprocating feed devices disposed for advancing the cut off label laterally; folder devices coöperating 70 with the said feed devices to fold the cut off edges; creaser rolls for receiving and creasing a label; a ratchet wheel for advancing said creaser rolls; a ratchet pawl for acting 75 on said ratchet wheel; and an eccentric on said shaft for actuating said pawl, as specified.
- In witness whereof, I have hereunto set my hand and seal in the presence of two witnesses. 80
